UNITED STATES PATENT OFFICE.

GEOFFREY MAXWELL BOUMPHREY, OF LYMM, ENGLAND.

CABINET.

Application filed March 22, 1923. Serial No. 623,960.

To all whom it may concern:

Be it known that I, GEOFFREY MAXWELL BOUMPHREY, a British subject, residing at Baycliffe, Lymm, county of Chester, England, have invented certain new and useful Improvements in Cabinets, of which the following is a specification.

This invention relates to cabinets such as used for storing gramophone and like disc records which are rotatable about a horizontal axis so that the records are normally stored in a horizontal position but are presented for inspection or withdrawal in a vertical or approximately vertical position.

15 My prior United States Patent No. 1,439,725 describes such a cabinet.

In accordance with my present invention, the lid of the container within the cabinet which covers a vertical side of the container 20 when the latter is in its closed or vertical position (the said side being uppermost when the container is open or in its horizontal position) is supported by the cabinet proper and the container has a combined 25 pivotal and rolling movement away from or towards said lid when being moved to a horizontal or to a vertical position respectively.

I am aware that coal and like bins have 30 been proposed in which the bin has a combined pivotal and rolling movement in being moved from a vertical to a horizontal position, such movement being obtained by means of quadrants or curved surfaces upon 35 the bin running upon rails upon the cabinet containing the bin.

The invention is illustrated in the accompanying drawings in which

40 Figures 1 and 2 show side elevations of the improved cabinet with a side panel removed and

Figure 3 is a side elevation of the movable box-like container.

45 Referring now to the drawing I provide a stand 1 which is provided with two lateral rails 2 which in the form shown have horizontal upper edges. The tilting box-like container 3 is provided with lateral fittings 4 having arcuate supporting edges 5. In 50 the form shown, the said fittings are shown as quadrants but it will be understood that any other convenient form of fixed rolling support may be provided. The box-like container rests by means of said fittings 4 on the rails 2, the closed position being shown 55 in Figure 1 and the open position in Figure

2. In the case illustrated the fittings 4 are so disposed with relation to the centre of gravity of the box when full, that it tends to open under gravity. It will be realized 60 that during tilting a corner of the box indicated at 6 will rise above its closed position and the said walls of the box are therefore suitably spaced from the top 7 of the stand in order to allow free movement, the front 8 65 of the box being upwardly extended as shown to provide a complete closure. Similarly the vertical inner edges of the walls of the box are spaced from the rear supports 9 of the stand. In the latter case, however, as 70 the box travels outwards during tilting, the amount of spacing required is not considerable. Fixedly secured to the rear supports 9 of the stand is a bellows 10 the front 75 hinged wall of which is connected by one or more pivoted links 11 to either or both fittings 2 and which serves as a cushioning device operating, in this case, when the box is opening.

The vertical lid 12 which closes the opening of the box when the device is shut is freely hinged at 13 by means of two horizontal arms or brackets 14 so arranged that when the lower inner corner of the box begins to rotate, the lid can move away therefrom and finally hangs in such a position shown in Figure 2 as will be engaged by the returning corner when the box is closed. Two lateral pins 15 provided at the lower 90 edges of the lid are adapted to be engaged by cam-shaped hooks 16 when the box closes so as to retain the lid in close contact with the walls of the box and exclude dust during storage. The box is provided with shelves 17 whereby the gramophone records 95 are enabled to be stored flat but presented for inspection and/or withdrawal in a vertical or approximately vertical position, and is held in the closed position by a spring catch 19.

100 It will be realized that owing to the forward movement of the box and consequent shifting of the virtual centre of rotation, the top 7 of the cabinet can be lowered without hindering the selection and withdrawal 105 of the hindmost records more than would be possible if the box rotated about fixed trunnions and the stand in consequence can be so designed with the present improvements as conveniently to serve for the support of a gramophone during use. Also the 110 back of cabinet can be brought forward.

The engaging surfaces of the box and the top of the stand are lined with felt to minimize shock and provide dust-proof closure, and the front edges of the quadrants 2 which in the form shown abut against the walls of recesses in the front supports of the stand in the open position may be similarly felted.

In order to prevent slip of the surfaces 5 on the rails 2 I provide flexible metal strips 18 secured as shown to the front ends of the side rails and the rear edges of the quadrants, it being understood that the rear ends of the said strips are bent upwards around 15 the curved surfaces of the quadrants during tilting, but any other suitable means of preventing slip may be provided.

I do not wish to be understood as limited to the provision of a bellows as any other 20 equivalent device such as springs or a dash pot may be provided for either or both movements of the box.

It is obvious that those skilled in the art 25 may vary the details of construction as well as the arrangement of parts without departing from the spirit of the invention, and therefore I do not wish to be limited to the above disclosure except as may be required by the claims.

I claim:

1. In gramophone and like cabinets, a stand, a pivotally mounted container therein, a lid for the container hingedly suspended from the stand top in a vertical position,

the container having an open side arranged 35 in a vertical plane when in a closed position against the lid, the said side being uppermost when the said container is open or in a horizontal position, the said container being also supported by the stand when in an 40 open position, means for effecting a combined pivotal and rolling movement of the container away from and towards said lid when being moved to a horizontal or to a vertical position respectively, and interlocking 45 means mounted on said container and lid for retaining said parts together when in a closed position.

2. A cabinet as claimed in claim 1, wherein interlocking means is mounted on the 50 container and stand for releasably holding the container in a closed position, substantially as described.

3. A cabinet as claimed in claim 1, wherein the means for effecting the combined pivotal and rolling movement of the container includes opposed side rails in the stand, segmental fittings secured to opposite sides of the cabinet having arcuate engaging surfaces for contacting with the rails, a cushioning device mounted in back of the stand, and link connections between the cushioning device and the fittings, substantially as described.

In testimony whereof I affix my signature.

GEOFFREY MAXWELL BOUMPHREY.
